Des. 1213

Francis Dorey, of New York, N.Y.
Letters Patent No. 1213, dated Mar. 20, 1860,

The schedule referred to in these Letters Patent, and making a part of the same,
To all whom it may concern:

Des. 1213

Be it known that S. Francis Hovey, of the City, County and State of New York, have produced a new and ornamental design for a Copying Press: and I do hereby declare that the following is a full, clear and exact description of the same, reference being had to the accompanying drawing forming a part of this Specification, which represents a front elevation of my invention.

This design consists in a new and ornamental form given to the parts forming the arch that supports the nut of the press spindle, and also in a new and ornamental form of said nut itself, and of the socket or step of the spindle fastened to the upper side of the platen, and it consists further in an ornamental form of the lever or handle of the press as will be hereafter more fully described.

To enable those skilled in the art to fully understand my design, I will proceed to describe it with reference to the drawing.

The bed plate or bottom A. of the press is formed in the usual manner and I have ornamented it with leaves a extending all round. On its sides and supported by stylobates B. rise the columns C. which in their turn are covered by entablatures D.

The lower portions of the stylobates resemble in their form the bedplate A. and like this they are ornamented by leaves, and they rise up on a series of fillets b. ovals c. beads d. and ovals d. to the base of the columns. The shafts of the columns themselves are square and provided with flutes e. as clearly shown in the drawing. These columns support the entablatures D. which consist of an oval, a bead and another oval, the inner sides of both columns being left flat and provided with grooves that form the guides for the platen E.

On the top of the entablature rests the heads of fishes F. the bodies of which are curled back, so as to bring the tails F. close behind the heads, and firmly secured to the bodies of said fishes, and right over the center of the platen E. is the boss G. that forms the nut for the press spindle H.

This nut is ornamented by flutes g. and its fluted part is terminated by a groove h. from which an oval i. leads to a fillet j. By these means the whole arc forms a beautiful and ornamental combination. The lever I. is secured to the top of the spindle by means of a boss k. which is thicker in the center and fluted from top to bottom, and fluted arms l. extend from either side of said boss. These arms connect by means of beads m. with the handles n.

3

Dec. 1213

The foot of the press spindle steps into a socket J, that is fastened to the platen in the usual manner. It is formed of a flange δ from which rises a spherical boss β , ornamented all round by leaves g , and surmounted by a cylindrical portion α .

The whole press thus formed has a very handsome and ornamental appearance, and as all its parts are cast in iron or brass, the expense of its construction is the same as that of ordinary presses for the same purpose, after the patterns are made.

What I claim as new, and desire to secure by Letters Patent, is
1st. The within described form of the columns C, fishes E, and nut & arranged as described, so as to compose a new and ornamental design for the arch of a Copying press.

2nd. The within described form of the lever I, consisting of a boss κ , fluted from top to bottom, in combination with fluted arms ℓ , beads m , and handles n as described, so as to produce a new, and ornamental design.

3rd. The within described form of the pocket J, composed of the flange δ , spherical boss β , ornamented by leaves g , and surmounted by a cylindrical portion α , in the manner herein specified.
